ATTORNEY.

UNITED STATES PATENT OFFICE.

NAT. W. PRATT, OF BROOKLYN, NEW YORK.

CONNECTING-BOX FOR SECTIONAL STEAM-BOILERS.

SPECIFICATION forming part of Letters Patent No. 368,610, dated August 23, 1887.

Application filed March 3, 1887. Serial No. 229,569. (No model.)

To all whom it may concern:

Be it known that I, NAT. W. PRATT, a citizen of the United States, residing at Brooklyn, county of Kings, and State of New York, have 5 invented certain new and useful Improvements in Connecting-Boxes for Sectional Steam-Boilers, of which the following is a specification.

This invention relates to the construction of boxes for use in making a connection between 10 a drum and a series of water-tubes of sectional water-tube steam-boilers; and the said invention consists in applying certain novel features of construction to the said boxes for the purpose of producing them from wrought metal.

15 In order to enable others skilled in the art to which my invention appertains to understand and use the same, I will proceed to describe the features of its construction, having reference to the accompanying drawings, and 20 subsequently point out in the appended claims its novel characteristics.

Figure 1 is an end elevation of a part of a drum and box connected in position thereto; Fig. 2, a central vertical section on the line 25 xx , Fig. 1; Fig. 3, a partial plan view of the connecting-box detached from the drum; Fig. 4, a cross-section on the line yy , Figs. 1 and 3, viewed in a direction opposite to that of Fig. 2; and Fig. 5, a central section of a part of the 30 connecting-box and drum taken on the line zz , Figs. 2 and 3.

The present construction consists in pressing from a sheet of wrought metal an open box, A, having a perimeter, a , for the reception of a flanged tube-sheet, A', and in pressing upon the top or back of the said open box a saddle depression, C, made to fit the curvature of the side of a drum, B. The saddle-depression and adjacent side of the drum have 40 corresponding perforations b , in which nipples c are inserted for connecting the said parts together and establishing communication.

The saddle-depression C presents in plan view an approximate oval form, bulging at f , 45 Figs. 1 and 2, which offers an increased flat-

tened surface for the reception of numerous perforations b .

The upper sides, g , of the box A are preferably inclined or converged at an angle toward the ends for compactness of form.

50 The tube-sheet A' presents at the bottom of the manifold a flat surface, d , having perforations e for the reception of water-tubes. For the purpose of entering the tubes at an angle other than a right angle to the axis of the drum 55 the said flat surface may be inclined in either direction to the said axis, or it may be parallel therewith.

In another application filed simultaneously herewith, Serial No. 229,576, the special construction shown in Fig. 5 of the present application is included in claims 6 and 7 of said other application.

What I claim as my invention, and desire to 60 secure by Letters Patent, is—

1. A wrought-metal connecting-box for water-tube boilers, made of two pieces, a saddle-box and a tube-sheet, riveted or welded together with substantially parallel sides swelled into an approximate oval where it joins the 65 drum, substantially as specified.

1. A wrought-metal connecting-box for water-tube boilers, made of two pieces, a saddle-box and a tube-sheet, riveted or welded together with substantially parallel sides swelled into an approximate oval where it joins the drum, and provided with 70 perforations in the saddle-face, through which it may be secured to and made to connect with a drum by nipples fixed in said perforations, substantially as specified.

3. A wrought-metal connection for water-tube boilers, having two sides substantially parallel through a great part of their surface, an approximately oval top perforated for tubes and curved to fit a drum, and a perforated 75 bottom, substantially as specified.

NAT. W. PRATT.
